UNITED STATES PATENT OFFICE

JOHN E. ROSBERG, OF SAN FRANCISCO, CALIFORNIA

APPARATUS FOR TREATING MEATS

Application filed June 25, 1930. Serial No. 463,627.

This invention pertains to an apparatus for curing meats and more particularly to an improved apparatus for the treating of meats by the injection of a fluid into the arteries thereof.

It is the object of the present invention to provide an improved type of apparatus by means of which meats may be cured by the injection of a fluid curing substance into the arteries of the meat.

I attain my object through the provision of a fluid container and a motor driven pump adapted to draw fluid from the container and force it through a conduit and a vein needle connected therewith. The vein needle is placed in an artery of the piece of meat to be cured and the fluid under pressure flows through the same and permeates the meat. A specially designed valve is placed in the conduit between the pump and the needle and this valve may be operated to cut off the supply of fluid to the needle and circulation through the fluid container and pump. The valve also operates an electric switch in the circuit from which the motor is energized, so that when the fluid flow through the needle is discontinued, the motor is automatically de-energized and the operation of the pump ceases.

One form which my invention may assume is exemplified in the accompanying drawings and following specification, from which a better understanding of the operation and construction of the device may be had.

In these drawings—Figure 1 is a perspective view of an apparatus embodying my invention,

Figure 2 is a side elevation of the same apparatus with parts shown in section,

Figure 3 is a sectional view of a vein needle of the type employed in this apparatus,

Figure 4 is an elevation of the fluid control valve and electric switch cooperating therewith,

Figure 5 is a sectional view taken on the line IV—IV of Figure 4,

Figure 6 is a sectional view taken on the line VI—VI of Figure 5, and

Figure 7 is a view similar to Figure 6

showing the position of the valve under different operating conditions.

Referring more particularly to the drawings and especially to—Figures 1 and 2, I show a container for curing fluids, or a brine tank 10. Positioned above the tank 10 is a portable pumping apparatus, generally indicated at 11. The pumping apparatus 11 consists of a small electric motor 12 and a pump 13. The pump 13 shown is of the gear type, but it is to be understood that any other suitable type of pump may be employed.

The pump 13 is provided with an inlet port 14 and an outlet port 15. A suitable conduit, such as a rubber hose 16, connects the inlet port of the pump with the brine in the tank 10. The hose 16 is provided with a strainer 17 at its intake end to prevent the flow of undesirable substances, that may accumulate in the brine tank, into the pump. The outlet port 15 of the pump 13 connects with a vein needle 18 by means of a conduit 19 and a hose 20. A valve 21, to be more fully described hereinafter, is interposed between the pump and the vein needle 18 and a pressure gauge 22 is connected with the conduit 19 between the valve 21 and the pump 15.

The construction of the vein needle 18 is best shown in Figure 3 of the drawings, in which it may be seen that the needle itself is tubular, or hollow, and is connected to the hose by means of a hose nipple 23, a threaded bushing 24, a threaded tube 25 and a packing nut 26. A suitable hose clamp such as is shown at 27 maintains engagement between the hose 20 and the nipple 23. The construction of the valve 21 is best shown in Figures 4 to 7, inclusive. The valve comprises a body portion 28 formed with an inlet port 29, a discharge port 30 and a return port 31. The valve body 28 is cylindrical and has a machined inner surface. A valve member 32 is closely fitted to and mounted for rotation within the valve body. A handle 33 is provided for rotating the valve member 32 and a cap 34 and packing member 35 maintain the valve member 32 in its proper position within the valve body. The valve member 32 is cylindrical and is provided with 100

ports 29a, 30a and 31a for cooperation with the ports 29, 30 and 31 formed in the valve body. The exterior of the cap 34 is provided with stops 36, which limit the movement of the handle 33 and consequently the rotation of the valve member 32 within the valve body. The port 29a within the valve member is of such a size that it is in communication with the intake port 29 of the valve at all times during its limited movement while the ports 30a and 31a are of approximately the same size as the ports 30 and 31.

Referring to Figure 1, it may be seen that the intake port 29 of the valve is in communication with the pump. The discharge port 30 leads to the needle 18, and the return port 31 is provided with a hose 37 which forms a return line to the brine in the tank 10.

In operation, the several parts are connected as shown. The motor 12 is then energized and drives the pump 13. Brine is drawn from the tank 10 into the pump through the hose 16 and discharged through the valve 21, which is in the position shown in Figure 6 and to the vein needle 18. The vein needle is then inserted into an artery of the piece of meat to be cured and the fluid under pressure passing through the needle flows through the arteries following the natural course taken by blood in these arteries. When the arteries become full, the pressure exerted by the pump causes the fluid to seep through their walls and permeate the meat. When the fluid is seen to ooze from the outer surface of the meat, the meat has been thoroughly treated and is removed, and this process is repeated on another piece of meat to be cured, and so on.

It has been found that for different types of meat, different pressures are required to procure the best results. In order to obtain varying pressures, the handle 33 of the valve 21 is moved to cause various positions of the ports 30a and 31a with respect to the ports 30 and 31. Referring to Figure 6, it may be seen that by moving the handle 33 a slight distance to the left, the port 30 would be open, while the port 31 would be closed.

Movement of the handle to the right would reverse the positions of these ports, and by moving the handle to intermediate positions, either one of the ports may be opened and the other closed to any desired degree. When the port 30 is open, the full pressure of the pump 13 is exerted through the needle 18. When the port 30 is partially closed, some of the fluid under pressure is permitted to escape through the return port 31 and the hose 37 back into the brine tank. The pressure in the line between the pump and the vein needle is indicated on the gauge 22 for the convenience of the operator.

A further advantage of the valve 21 lies in the fact that the ports 30a and 31a are so

positioned with respect to the ports 30 and 31 that when it is desired to shut off the flow through the port 30 altogether, a connection is formed between the ports 31 and 31a before the port 30 is entirely closed, making it impossible to build up an excessive pressure between the pump 13 and the valve 21.

The valve 21 has an electric snap switch 38 of standard design secured to it. This switch is interposed in a conducting wire 39, which forms a part of the circuit to the motor 12. The switch is operated by means of a lever 40 resiliently held in an upward position by a spring 41. A projection 42 on the handle 33 of the valve contacts with this lever when the port 30 is open. This projection depresses the lever 42 and completes the circuit through the conducting wire 39, energizing the motor 12. When the port 30 is closed, the lever 40 on the switch is released and the motor is de-energized; thus, as soon as the fluid under pressure is cut off from the needle 18, the motor 12 is automatically de-energized and the pumping operation ceases.

The several parts of the apparatus that come in contact with the brine, or whatever sort of fluid is being used, are formed of materials that will resist the deleterious effect of the fluid.

While I have shown a preferred form of my invention, it should be understood that various changes may be resorted to in the construction and arrangement of its several parts without departing from the scope of the appended claims.

Having thus described my invention, what I claim and desire to secure by Letters Patent is

1. An apparatus for treating meats comprising a pump, a source of fluid supply, means for directing fluid under pressure from said pump to the arteries of a piece of meat, a conduit between said means and said pump, and a valve in said conduit, said valve being adapted to direct part of the fluid from said pump to the meat and part back to the source of supply whereby the pressure of the fluid directed into the meat may be regulated and the source of supply may be kept in a state of constant agitation.

2. An apparatus for treating meats comprising a pump, a source of fluid supply, means for directing fluid under pressure from said pump to the arteries of a piece of meat, a conduit between said means and said pump, a valve in said conduit for cutting off the flow of fluid from the pump to the meat and directing said flow to said source of supply, said valve being so constructed as to direct said fluid to the source of supply before cutting off the flow of fluid from the pump to the meat, thereby preventing excessive pressure between the valve and the pump.

3. An apparatus for treating meats, com-

prising a pump in communication with a source of fluid supply, a vein needle for injection into the meat, a conduit between the pump and vein needle, a by-pass from said conduit and said source of supply, and valve means connected with the conduit and by-pass and adapted to direct a flow of fluid through the by-pass to agitate the source of fluid supply while fluid is passing through the conduit to the vein needle.
